CLYDE B. FAVERTY, OF HAMMOND, INDIANA, AND WILLIAM J. SCHLACKS, OF CHICAGO, ILLINOIS, ASSIGNEES TO RYAN MANUFACTURING CORPORATION, OF CHICAGO, ILLINOIS, A CORPORATION OF ILLINOIS

DOUBLE REVERSIBLE MOLDBOARD FOR GRADERS

Application filed May 4, 1927. Serial No. 188,805.

Our invention relates to road graders and has to do more particularly with the mold board and supporting means therefor for graders, an object being to provide an improved arrangement of the above character having certain advantages and features hereinafter more fully pointed out.

More particularly, our aim was to produce an underslung double reversible mold board for graders, having rigid supporting means permitting ready adjustment of the mold board both longitudinally and tiltably with means for positively holding it in any adjusted position. Another feature of our invention is the provision of supporting means permitting reversing of the mold board without necessarily lifting it off of its supporting brackets, and double removable cutting edges on the reversible board. Other features will be apparent from the ensuing part of the specification and appended claims.

For a better understanding of our invention reference is to be had to the accompanying drawings, in which—

Fig. 1 is a plan view of a typical circle frame with our improved mold board suspended therefrom;

Fig. 2 is a front view of Fig. 1 but with the circle frame in section;

Fig. 3 is an end view of the mold board and one supporting bracket, showing the mold board in different positions by full and dotted lines; and

Fig. 4 is a rear view of a part of the mold board showing the supporting bracket and holding and adjusting means for the board.

Referring now more in detail to the preferred construction employed, we show a mold board consisting of the main blade 5 which may be of any suitable construction but preferably sheet steel formed at its opposite longitudinal edges to receive the cutting blades 6—7 preferably constructed of steel which may be suitably hardened for the work to be performed. These blades or cutting

edges 6—7 are preferably readily removably attached to the main blade 5 and to this end are secured by bolts 8 which pass through the cutting edges and main blade and are adapted to clamp them together, so that each cutting edge acts as an uninterrupted continuation of the main blade.

The mold board with its double cutting edge is suspended so as to be reversible to use either cutting edge, or face it in either direction without removing it, or lifting or dropping it from its supports and to this end we provide right and left brackets 9, each having an upper horizontal extending portion 9' shaped to be attached to the outside of a circle frame as 10. These brackets may be secured in any suitable manner, such as by bolts or rivets passing through the holes 11 therein and through or into the circle frame 10. The brackets each have a downwardly extending portion 9² terminating in the mold board attaching end through which a shaft 12 extends, which shaft is rotatably and longitudinally adjustably held in the bracket end so as to permit a corresponding adjustment of the mold board. This shaft 12 is supported in a pair of brackets 13—14 suitably secured to the main blade of the mold board, preferably by being riveted thereto. The shaft 12 is preferably non-rotatably held in the brackets 13—14 by suitable pins 15 which pass through the bracket heads and shaft 12 as indicated. It will be noted that the shaft 12 is of such length as to permit longitudinal adjustment of the mold board and this length may be varied depending upon the extent of the adjustment desired. As shown in Figs. 1 and 2, there is such a supporting shaft for each bracket 9 on the opposite sides of the circle frame, this separate construction being preferable to one continuous shaft 12 as it has certain advantages. It will thus be seen that with the mold board suspended by the shafts 12 and two support-

ing brackets 9, it has both longitudinal and tilttable adjustment.

As previously stated, a feature of our invention is a longitudinal and tilttable adjustment which also is of such construction as to permit reversal of the mold board without necessarily removing it or dropping it off the supporting brackets. To this end we provide a series of upper and lower right and left bracket pairs 16-17 and 18-19 respectively, suitably spaced so as to permit longitudinal adjustment of the mold board within its limits, and said bracket pairs each being adapted to readily removably support an adjusting screw 20. This adjusting screw 20 is preferably pivotally held at its head by a shaft 21 which passes through the brackets 16-17 and suitably held therein as by a cotter pin 22. This screw 20 then passes through the eye of a stud 23 which is pivotally held in the bracket 9 as indicated at the sectional portion in Fig. 4, so as to allow swinging of the screw 20 when the mold board is pivotally adjusted by the nuts 24, and also to allow swinging each bolt 20 from one position to the other to engage the proper bracket pair 16-17 or 18-19 without adjustment when the mold board is reversed or swung from one facing position to another as indicated by the dotted line positions in Fig. 3. The lock nuts 24 are threaded upon the screw 20 so as to lock it and the mold board in any tilted position. In Fig. 3 the full lines show the mold board in a vertical position and the dotted lines to the left indicate the mold board tilted slightly into one of its angular adjustments.

As previously stated, the adjusting screw 20 is adapted for interchangeable support in any of the paired brackets 16-17, or in 18-19 when the mold board is reversed, and in the embodiment of our invention illustrated we show five bracket pairs, thus permitting five points longitudinal adjustment. This is sufficient for ordinary operating conditions, although it will be apparent that the number of positions may be increased or decreased within the limits of desired longitudinal adjustment. Each row of bracket pairs 16-17 and 18-19 respectively, is mounted upon an angle iron as 25 which preferably extends throughout the length of the mold board, or rather from the extreme end bracket pair as 16-17 at one end to the extreme bracket pair at the other end, thus also serving as a brace to strengthen the mold board longitudinally. These brackets are riveted by both angles into the angle of the bar 25 and thus the brackets and bar 25 strengthen each other.

In order to positively lock the mold board in any of its longitudinally adjusted positions and prevent shifting thereof by the extreme pressure placed thereon during operation, we have provided a novel construction

70 permitting positive interlocking of the brackets and mold board in its different longitudinal positions. To this end interengaging or abutting elements on the mold board and suspending brackets 9 are supplied. Thus each main supporting bracket 9 is provided at its lower end with a lug as 26 adapted to enter the proper slot as 27 in a bar 28 secured to the rear face of the mold board, preferably by being riveted thereto. With the mold board adjusted at one extreme position, as indicated in Fig. 4, the adjusting screw 20 is in the first bracket pair 16-17, in which case the lug 26 has entered the first slot 27. With the mold board adjusted to the second position, the screw 20 would of course be in the second pair of brackets 16-17 and the lug 26 would enter the second slot 27, and so on, depending upon the point of longitudinal adjustment.

75 It will be noted that the main supporting bracket has an oppositely extending lug 26', this being provided for cooperation with the mold board when it is moved to a reversed or oppositely facing position as indicated by the dotted lines to the right in Fig. 3.

80 Assuming that the mold board is to be reversed, that is, moved to the opposite side of the brackets 9, the adjusting screw 20 is released from the mold board and this may be done by withdrawing the cotter pin 22 from the pin 21 of each adjusting screw, permitting this pin 21 to be withdrawn so as to free the mold board. The mold board may now be dropped down so as to hang from the brackets 9 as indicated by the lower dotted line position of Fig. 3, and then moved up into position on the opposite side of the brackets. This will bring a lower bracket pair 18-19 up for engagement with each adjusting screw 20, and therefore the head of the screw is permitted to enter between the proper bracket pair 18-19 and the pin 21 inserted. This operation, of course, is performed at each one of the two supporting brackets 9 and may be made without any adjustment of the screws 20. The mold board may then be tiltably adjusted to any desired position by manipulating the lock nuts 24 at each of the two adjusting screws 20. As the mold board is swung from one position to the other, the lug 26' enters the appropriate slot 27 in the bar 28 on the rear face of the mold board, so as to lock it against longitudinal shifting.

85 90 95 100 105 110 115 120 125 130 From the foregoing it will be seen that we have provided an improved underslung double reversible mold board which may be reversed so as to face in either direction from the center of the circle frame and without removing it from its supporting brackets; in which the mold board may be tiltably adjusted in either of its two facing positions; in which longitudinal adjustment is permitted but interlocking means are provided

for positively holding the mold board against longitudinal shifting during operation; and a symmetrical mold board for the above construction having double removable cutting edges or blades whereby the mold board may be reversed into either of two opposite operating positions and held in identical adjustment in each position.

There are other advantages in construction and in operation, depending to some extent upon the method of applying the mold board and suspending brackets to the circle frame or other holding means, and we contemplate constructing and using our invention in other ways than herein shown and therefore do not desire to be limited to the exact arrangement illustrated and described, but aim to cover all that which comes within the spirit and scope of the appended claims.

What we claim as new and desire to secure by United States Letters Patent is:—

1. In a road grader, mold board supporting brackets, a mold board, means for pivotally attaching the mold board to said brackets to swing the mold board on the brackets from one facing position into an opposite facing position relative to the brackets while supported thereby, and adjusting means for tiltably adjusting and holding the mold board in various tilted positions while in either said facing position.

2. In a road grader, mold board supporting brackets, a mold board, and means for pivotally suspending the mold board from said brackets to swing the mold board on the brackets from one facing position into an opposite facing position relative to the brackets while supported thereby, said suspending means including longitudinally adjustable supporting elements for permitting longitudinal adjustment of the mold board in either said facing position.

3. In a road grader, mold board supporting brackets, a mold board, means for pivotally suspending the mold board from said brackets to swing the mold board on the brackets from one facing position into an opposite facing position relative to the brackets while supported thereby, said suspending means including longitudinally adjustable supporting elements for permitting longitudinal adjustment of the mold board in either said facing position, and interengaging elements for the mold board and brackets for positively holding the mold board in any longitudinally adjusted position.

4. In a road grader, mold board supporting brackets, a mold board, means for pivotally attaching the mold board to said brackets to swing the mold board on the brackets from one facing position into an opposite facing position relative to the brackets while supported thereby, said attaching means including longitudinally adjustable elements for also permitting longitudinally adjusting the

mold board in either said facing position, and interengaging elements for the mold board and brackets for positively holding the mold board in its longitudinally adjusted position, said interengaging elements comprising longitudinally abutting means for each bracket and the mold board.

5. In a road grader, mold board supporting brackets, a mold board, means for pivotally attaching the mold board to said brackets to swing the mold board on the brackets from one facing position into an opposite facing position relative to the brackets while supported thereby, said attaching means including longitudinally adjustable elements for also permitting longitudinally adjusting the mold board in either said facing position, links adjustably connecting the brackets and mold board, and a series of spaced brackets for receiving each adjusting link, the bracket used being determined by the longitudinal adjustment of the mold board.

6. In a road grader, mold board supporting brackets, a mold board, means for pivotally attaching the mold board to said brackets to swing the mold board on the brackets from one facing position into an opposite facing position relative to the brackets while supported thereby, said attaching means including supporting shafts for also permitting longitudinally adjusting the mold board in either said facing position, links adjustably connecting the brackets and mold board, and a series of spaced brackets for receiving each adjusting link, the bracket used being determined by the longitudinal adjustment of the mold board, said brackets being spaced along opposite cutting edges of the mold board for use with the adjusting links with the mold board in a corresponding facing position.

7. In a road grader, mold board supporting brackets, a mold board longitudinally adjustably carried by said brackets, shiftable adjusting links movable into positions corresponding to the longitudinally adjusted positions of the mold board and connecting the brackets and mold board for tiltably adjusting the latter, an angled reinforcing bar secured longitudinally to the rear face of the mold board, and adjusting link holding brackets secured to the angled bar and spaced to afford the said longitudinal positions of the adjusting links.

8. In a road grader, a symmetrically formed double cutting edge mold board, means for pivotally supporting the mold board for shifting it on its pivotal support into either one of two opposite facing positions without removing it from its pivotal supporting means, and whereby a cutting edge is put into operating position with either facing position of the mold board, a mold board adjusting link pivotally carried by each bracket to be swung into positions corresponding to the two facing positions of the mold board, and

means for securing the adjusting link in either position to the mold board.

9. In a road grader, mold board supporting brackets, a mold board, a longitudinal shaft journaled in the brackets to permit longitudinal adjustment of the mold board, lugs carried by the brackets and a bar carried by the mold board and having notches for receiving said lugs, the lugs entering the notches when the mold board is in operating position so that accidental longitudinal shifting of the mold board is positively prevented.
